UNITED STATES PATENT OFFICE.

OTTO SELG, OF NEW YORK, N. Y.

MASHING APPARATUS.

SPECIFICATION forming part of Letters Patent No. 628,232, dated July 4, 1899.

Application filed February 20, 1899. Serial No. 706,111. (No model.)

To all whom it may concern:

Be it known that I, OTTO SELG, a citizen of the United States, and a resident of New York, (Brooklyn,) State of New York, have invented 5 certain new and useful Improvements in Mashing Apparatus, of which the following is a specification.

This invention relates to a mashing apparatus used in brewing beer and similar beverages, which is so constructed that the entire contents of the tub are thoroughly acted upon by the liquids, steam, and compressed air introduced, and that more particularly the formation of a "dead" layer upon the 15 bottom of the tub is avoided.

In the accompanying drawings, Figure 1 is a vertical longitudinal section of my improved mashing apparatus; and Fig. 2 is a horizontal section on line 2 2, Fig. 1.

The letter A represents the mash-tub, provided with a concave bottom *a* and a corresponding perforated false bottom *a'*, adapted to concentrate the grain into a closely-packed body. The steam, thin mash, air, and water 20 are adapted to be fed into the tub by two different pipes or pipe systems, the one entering through the bottom *a* and the other arranged within the body of the tub directly above the false bottom *a'*. Thus in the drawings the main conduit-pipe *b* connects at the top with the steam-pipe *c*, thin mash-pipe *d*, water-pipe *e*, and compressed-air pipe *f*, while at the bottom it divides into two branches *g* and *h*.

The branch *g*, controlled by cock *g'*, is a circular pipe placed against the inner wall of tub A directly above the false bottom *a'*. It has a number of downwardly-opening perforations *g''*, through which the contents of the 30 pipe are blown from above into the lower stratum of the mash supported upon the false bottom, so as to thoroughly penetrate the same. The branch *h*, controlled by cock *h'*, enters the central opening *a''* of the bottom 35 *a* above the discharge-gate *a'''* and blows the contents of the pipe into the mash from below. Thus by means of the combined action of the branches *g* *h* the malt is thoroughly

acted upon by the steam, compressed air, and liquids introduced, and the settlement upon 50 the false bottom of a body of malt which is not thoroughly worked up and saturated is avoided.

The stirrer is composed of a number of obliquely-set blades *i* *i'*, secured to opposite 55 ends of a series of arms *i''*, mounted upon the power-shaft *i'''*. The blades *i* connect adjoining pairs of arms *i''* at one end, while the blades *i'* connect the intermediate pair at the opposite end, so that in this way an opening 60 is formed at the ends of the arms between each adjoining set of blades. This peculiar construction of the stirrer enables it to freely enter the mash and agitate the same in a very 65 perfect manner.

The arms *i''* increase in length from the periphery toward the center of the tub A, and the blades *i* *i'* are curved to conform to the curvature of the false bottom *a'*, so that they 70 may sweep freely over such bottom.

As the tube *g* is located above the false bottom, it is clear that the malt supported upon the latter is thoroughly agitated and washed out, so that all the extract is effectively withdrawn. Moreover, by admitting steam, hot water, or air to the tub simultaneously from its 75 inner and outer side the mash becomes thoroughly and uniformly impregnated throughout its body, so that a superior wort is obtained.

What I claim is—

In a mashing apparatus, the combination of a mash-tub having a curved bottom and a perforated curved false bottom, with a circular inner perforated tube above the false 85 bottom, an outer tube opening into the tub-bottom, and means for feeding liquids, steam or compressed air into said tubes, substantially as specified.

Signed by me, at New York city, New York, 90 this 18th day of February, 1899.

OTTO SELG.
